UNITED STATES PATENT OFFICE.

SIEGFRIED HENRY KAUFMANN, OF LONDON, ENGLAND.

MANICURE CASE.

1,424,571.

Specification of Letters Patent. Patented Aug. 1, 1922.

Application filed October 19, 1921. Serial No. 508,828.

To all whom it may concern:

Be it known that I, SIEGFRIED HENRY KAUFMANN, subject of the King of Great Britain and Ireland, and residing at 42 Tot-
5 tenham Street, Tottenham Court Road, in the county of London, England, have in-
vented certain new and useful Improvements
in Manicure Cases, of which the following
is a specification.

10 My invention relates to an improved con-
struction and arrangement of case for hold-
ing sets of instruments for manicure and like
purposes.

According to this invention, I employ a
15 base upon which is mounted a hollow pedes-
tal, on which the various articles of a set
of manicure instruments or the like are
mounted. This hollow pedestal is preferably
20 of substantially D-shape and is provided
with a vertical slot running substantially
from top to bottom of the curved side and
down the centre thereof. This slot serves
25 for the reception of the handle of a nail
polisher or brush, the handle of which is
mounted upon the back thereof and engages
in this slot, whilst the polisher or brush is lo-
cated within the interior of the hollow ped-
30 estal.

Around the exterior of the curved portion
30 of the hollow pedestal, are provided a series
of loops in which various instruments such
as a nail file, scraper knife, or knives may be
inserted, so as to retain them in an upright
35 position upon the exterior of the pedestal.
Upon the opposite side of the D-shaped ped-
estal is provided a retaining loop or slot for
the reception of a pair of nail scissors, and
a further loop is also provided in which may
40 be mounted a tube of polishing paste or the
like.

An outer cover of suitable shape is adapted
to be placed over the hollow pedestal and
the instruments mounted thereon, and this
45 cover engages at its lower end with the base
of the pedestal, upon which it may be a tight
fit, or may be otherwise secured. In the
upper end of this cover may be provided a
50 box having a detachable lid or cover secured
at one edge by a tape or other suitable
hinge. This box may be employed for the
reception of face powder and puff or other
suitable material, and may have a mirror
55 fixed in the lid.

The case may be made of any suitable
55 shape being either cylindrical, triangular,
square, or other suitable shape, the upright

cover being mounted upon a similarly
shaped base. The base is so arranged that
the pedestal with the instruments thereon
will readily stand in an upright position 60
and when the cover is removed, these instru-
ments will be supported in an upright posi-
tion and readily accessible for use as re-
quired, it only being necessary to lift each
instrument out of its retaining loop or to 65
remove the polisher or brush from the in-
terior of the hollow pedestal by sliding its
handle upwardly along the slot so as to dis-
engage it therefrom.

In order that my invention may be more 70
readily understood, reference is made to the
accompanying drawings in which:—

Figure 1 is a part sectional elevation of
a case for sets of manicure and like instru-
ments according to my invention, having the 75
cover partly broken away so as to show the
interior.

Figure 2 is an elevation of the inner por-
tion of the case with the cover removed look-
ing upon the same from the opposite side to 80
Figure 1.

Figure 3 is a plan of Figure 2, and

Figure 4 shows a modification, in which
a powder box and puff is provided in the
top of the outer cover. 85

Referring to the drawings, the base 1 is
provided with a cylindrical portion 2 over
which the lower ends 3 of the tubular or
other shaped cover 4 fits so as to enclose the
instruments mounted upon the hollow pillar 90
5. This hollow pillar 5 is secured upon the
cylindrical portion 2 of the base 1 so as to
stand in an upright position on its upper sur-
face.

A flat portion 6 is provided on one side 95
of the hollow pillar 5 for the reception of
the nail scissors 7 and upon the opposite side
of the pillar is provided a vertical slot 8
in which engages the handle 9 of the nail
polisher 10, the polisher itself lying within 100
the interior of the hollow pillar 5 and adapt-
ed to be removed by sliding the handle 9 up-
wardly along the slot 8 so as to withdraw
the polisher 10 from the upper end of the
pillar 5. Other instruments 11 such as a 105
file, pusher, cuticle knife, button hook, or
the like are mounted in leather loops 12 ar-
ranged round the sides of the hollow pillar 5
so that these instruments are supported in
a vertical position upon its sides and are at 110
once available and readily removed as re-
quired for use. Upon the flat portion 6 of

the pillar 5 and upon opposite sides of the scissors 7, are mounted a tube of polishing paste 13 and a bundle of orange sticks 14 in suitable leather loops 12 as used for the other instruments. The cover 4 is shaped to suit the base 2 and fits tightly over the same so that when it is pressed down over the portion 2 of the base it will be firmly held in position and will enclose the whole of the instrument.

In a modification illustrated in Figure 4 a small compartment 15 may be provided in the upper end of the cover 4 for the purpose of holding face powder or the like, and a suitable powder puff 16 may be provided in this compartment. A cylindrical lid 17 is mounted upon any suitable tape or other hinge at one side and is adapted to fit over the top of the compartment 15 so as to enclose the same. A small mirror 18 may be provided in the top of this lid.

While I have shown the case as being of a cylindrical shape it may be conveniently constructed in other forms, such as square, triangular, oval or the like, without departing from the nature of the invention, the outer cover and the upper portion of the base being made of the required shape to conform with each other.

30 I claim.

1. In a manicure case, a base, an upright hollow pillar mounted on this base, a vertical slot in one side of the hollow pillar to support a nail polisher in its interior, a series of loops around its exterior for the reception of various instruments and a cover adapted to fit over and enclose the whole and to engage the base so as to be held in position.

40 2. In a manicure case, a base, an upright hollow pillar mounted on this base, means for supporting instruments in the interior and around the outside of the hollow pillar, a flat side to the upright pillar upon which the scissors are mounted, and a cover adapted to fit over and enclose the whole and to engage the base so as to be held in position.

3. In a manicure case, a base, an upright hollow pillar mounted on this base, a vertical slot in one side of the hollow pillar to support a nail polisher in its interior, a series of loops around its exterior for the reception of various instruments, a flat side to the upright pillar upon which the scissors are mounted and a cover adapted to fit over and enclose the whole and to engage the base so as to be held in position.

4. In a manicure case, a base, an upright hollow pillar mounted on this base, means for supporting instruments in the interior and around the outside of the hollow pillar and a cover adapted to fit over and enclose the whole and to engage the base so as to be held in position, a compartment in the top

of the cover for powder and powder puff, a removable lid to this compartment and a mirror in this lid.

5. In a manicure case, a base, an upright hollow pillar mounted on this base, a vertical slot in one side of the hollow pillar to support a nail polisher in its interior, a series of loops around its exterior for the reception of various instruments and a cover adapted to fit over and enclose the whole and to engage the base so as to be held in position, a compartment in the top of the cover for powder and powder puff, a removable lid to this compartment and a mirror in this lid.

6. In a manicure case, a base, an upright hollow pillar mounted on this base, means for supporting instruments in the interior and around the outside of the hollow pillar, a flat side to the upright pillar upon which the scissors are mounted, and a cover adapted to fit over and enclose the whole and to engage the base so as to be held in position, a compartment in the top of the cover for powder and powder puff, a removable lid to this compartment and a mirror in this lid.

7. In a manicure case, a base, an upright hollow pillar mounted on this base, a vertical slot in one side of the hollow pillar to support a nail polisher in its interior, a series of loops around its exterior for the reception of various instruments, a flat side to the upright pillar upon which the scissors are mounted and a cover adapted to fit over and enclose the whole and to engage the base so as to be held in position, a compartment in the top of the cover for powder and powder puff, a removable lid to this compartment and a mirror in this lid.

8. In a manicure case, a circular base, a D-shaped upright pillar on this base, loops on the flat side of this pillar for the reception of the scissors, a vertical slot opposite to the flat side to engage the handle of a nail polisher located inside the hollow pillar, a series of loops on the curved exterior for the reception of other instruments, and a cylindrical cover to be placed over the upright pillar and to engage the circular base.

9. In a manicure case, a circular base, a D-shaped upright pillar on this base, loops on the flat side of this pillar for the reception of the scissors, a vertical slot opposite to the flat side to engage the handle of a nail polisher located inside the hollow pillar, a series of loops on the curved exterior for the reception of other instruments, and a cylindrical cover to be placed over the upright pillar and to engage the circular base, a compartment in the top of the cover for powder and powder puff, a removable lid to this compartment and a mirror in this lid.

SIEGFRIED HENRY KAUFMANN.
